(57) **CLAIM**

The ornamental design for a remote control operated light plug, as shown and described.

DESCRIPTION

FIG. 1 is a top perspective view of a remote control operated light plug;

FIG. 2 is a bottom perspective view of the remote control operated light plug;

FIG. 3 is a front view of the remote control operated light plug;

FIG. 4 is a rear view of the remote control operated light plug;

FIG. 5 is a left side view of the remote control operated light plug; the right side view is a mirror image thereof;

FIG. 6 is a top view of the remote control operated light plug; and,

FIG. 7 is a bottom view of the remote control operated light plug.

The broken lines of FIGS. 2 and 7 illustrate portions of the remote control operated light plug that form no part of the claimed design.
